UNITED STATES PATENT OFFICE.

WILLIAM H. IZARD, OF BELTON, TEXAS.

BAND-CUTTER AND FEEDER.

SPECIFICATION forming part of Letters Patent No. 439,277, dated October 28, 1890.

Application filed July 9, 1890. Serial No. 358,159. (No model.)

To all whom it may concern:

Be it known that I, WILLIAM H. IZARD, a citizen of the United States, residing at Belton, in the county of Bell and State of Texas, have invented a new and useful Band-Cutter and Feeder, of which the following is a specification.

This invention relates to band-cutters and feeders adapted to be employed in connection with thrashing-machines; and the object thereof is to provide a machine of this character which will receive the sheaves, cut their bands, spread the grain, and feed it forward in regulated quantities and at stated intervals, all in a manner and by mechanism effecting improvements upon devices of this character heretofore constructed.

To this end the invention consists of the specific construction and relative arrangement of parts, hereinafter more fully set forth, and illustrated in the drawings, in which—

Figure 1 is a general perspective view of this machine complete. Fig. 2 is a central longitudinal, and Fig. 3 a central transverse, section of said machine, the latter being taken on line 33 of Fig. 2. Fig. 4 is a front end view. Fig. 5 is a plan of the entire machine with the hinged table-leaves removed. Fig. 6 is an elevation of the left side of this machine. Fig. 7 is a detail in perspective of the trough and its operating mechanism. Fig. 8 is a detail perspective of the mutilated gear.

The frame-work of this machine comprises longitudinal side beams F, connected by vertical end beams H at the front and B at the rear, each of which pair of vertical beams carry cross-beams A at the ends of the machine, as shown in the several views of the drawings.

Upon blocks C at the outer ends of the cross-beam A, which is at the rear end of the machine, are mounted short horizontal beams D, which are in the same horizontal plane with the cross-beam A at the front end of the machine, and these short beams D are connected with said front cross-beams A by boards, forming tables S along the top of each side of the machine, as best seen in Fig. 1.

The cross-beam A at the rear end of the machine is adapted to rest upon the front frame of the thrashing-machine, a part of which is shown in dotted lines, and projecting down-

wardly from the lower ends of the vertical beams B and from a block E, connecting them, are braces 30, that are extended and connected to the cross-sill of the thrashing-machine, so as to hold the band-cutter and feeder in proper relative position thereto, as will be understood. Metallic straps or other suitable connections 35 are preferably attached to the cross-beam A at the rear end of the machine, and are to be connected to the front frame of the thrashing-machine upon which this beam rests, the connection being effected by screws or bolts or any suitable manner.

At each end of each table S is a journal-box 23, in which is mounted a shaft 23', carrying at the front end of the machine a double-grooved pulley 24, and over these two grooved pulleys passes a twisted belt 24'.

Mounted upon each shaft 23' is a hinged table M, having two pairs of longitudinal slots R through its body, and over a roller on the shaft 23' and a similar roller m in the outer edge of the table passes an endless belt or apron N.

In the frame-work of the hinged table-leaves are pins n, which engage notches in the edge of a slot 36' in legs 36, which extend thence downwardly to the ground, as best seen in Fig. 1.

The main operating-shaft 50 is journaled in boxes 1, secured upon the upright beams B, and is driven by a belt 51, leading from the thrashing-machine or from a suitable source of power, over a pulley 21, as shown. This shaft is connected by bevel-gears 52 with a longitudinal shaft 60, journaled in boxes 2 along the left-hand side of the machine, as shown in Fig. 6. The latter shaft is connected by bevel-gears 61 with a shaft 70, mounted in boxes 4, carried by the vertical beams H at the front end of the machine.

Mounted in boxes 5, just above those numbered 4, is a shaft 80, which I shall call the "knife-operating shaft," because it drives the knife, and on the right-hand end of this shaft is a crank 82, to which is connected a pitman 13, having a slot 83, loosely engaging a pin 84 in one of the side beams F of the frame-work, as shown in Figs. 2 and 6. The other end of the pitman 13 is pivoted to a crank 85, which is keyed to one end of a transverse finger-

shaft 90, journaled in boxes 10, carried on the lower edges of the side beams F and extending across beneath the machine. A belt 150 connects the pulley 21 with another pulley 22 upon one end of a shaft 101, journaled in bearings 107, carried on the lower edges of the side beams F near the rear end of the machine, and this shaft communicates motion through intermeshing bevel-gears 14 to 10 a vertical shaft 102, journaled in a block Q, located between the two beams F, the upper end of which vertical shaft has a crank 103. In this manner power which is applied to the drive-pulley 21 communicates motion to the 15 various parts of the machine.

8 is a fork whose prongs extend through transverse slots s in the table S, and whose body has a slot 62, engaging a pin 63, carried in the outer end of a bracket 3, secured to 20 the left-hand side beam F, and the lower end of this fork has a notch 64, which engages a crank 65, formed in the body of the longitudinal shaft 60. There is a similar fork at the opposite side of the machine whose lower 25 end is pivoted to a slotted pitman 9, the body of which slides loosely on a pin 6, carried by a bracket 7 beneath the machine, and the other end of which has a notch 66, also engaging said crank 65 on the longitudinal shaft 30 60. By this means the two forks 8 are caused to operate alternately, each rising through the outer ends of the slots s and moving inwardly therein, then descending and returning to the point of starting, and the forks are 35 guided in their movement and directed into the slots s by fingers 38, as seen in Fig. 6.

In the opening between the two tables S and at each side thereof is a longitudinally-slotted guide-track 11, and in these tracks 40 travel the feet o of a block 19, which supports the trough O. The latter travels longitudinally within this opening and is forced normally to the rear—that is, toward the thrashing-machine—by a spring 110, as shown 45 in Fig. 2. At the front end of this trough is an upright end piece U, having a notch 111, for a purpose to appear hereinafter, and connected to this end piece is a right-angled bracket 112, provided with a longitudinal slot 50 113 in its lower member, through which passes a set-screw 114 into the bottom of the trough. By this means the end piece can be adjusted as desired within the trough. The other end of the latter has wings P at its sides normally 55 distended (when the trough is projected to the rear, as seen in Fig. 5) by straps 115, which connect the free ends of the wings with the short horizontal beams D. The bottom of the trough O is extended, as at O', so as to be of 60 the same length as the wings P when folded, Fig. 2, and in this extension are seated fingers 117, for a purpose to appear later on. The block 19 carries two rollers 118, which are, respectively, engaged by the fingers 26, which 65 are mounted upon the finger-shaft 90, hereinbefore described, and when said shaft is rotated the fingers draw the block, and with it

the trough, forwardly against the tension of said spring, the latter suddenly returning said parts when the fingers disengage the two rollers in a manner which will be understood.

In some cases it may be desirable to provide a releasing-bar or trip-lever 119, pivoted in one of the tracks 11 and engaging a pin 75 upon the trough, and the lower end of this lever is operated at proper moments by a cam 27, adjustably mounted upon the finger-shaft 90 by a set-screw 26'. The function of this tripping-lever is to hold the trough retracted until one of the forks 8 has fed a bundle into it, and then to release the trough and allow its spring to throw it suddenly outward; but it will be obvious that nearly the same result could be accomplished by setting the fingers 85 26 upon the finger-shaft by their set-screw 26'.

The letter I designates a central beam at the front end of the frame-work and projecting above the tables S, and to the upper end of this beam is connected bars L, braced by 90 an inclined piece K, as seen in Fig. 2.

Journaled across the outer end of the bars L is a shaft 16', carrying a band-cutting knife 18, which is adapted to move through the notch 111 in the end piece U of the trough, 95 and also carrying a sprocket-wheel 16. Over said sprocket-wheel passes a chain, which leads over idle-pulleys 17', carried by stub-shafts 17 at the upper end of the post I, and passes over another sprocket-wheel 81, keyed 100 on the knife-operating shaft above mentioned. By this means as soon as the bundle of grain is dropped into the trough the rapidly-rotating band-cutting knife 18 severs the band around the same and allows the grain to be 105 scattered within the trough before it is fed therefrom to the thrashing-machine, this scattering being assisted by the fingers 117 in the extension O', as above stated.

The shaft 70 has a spline 71, and on this shaft is mounted a mutilated gear 15, which has a groove 72 engaging said spline, whereby it must revolve with but can be moved longitudinally upon the shaft, and any suitable means may be provided for so moving it longitudinally, as will be understood, or it may be held in position by a set-screw 73, as seen in Fig. 8. The face of this mutilated gear at one side is provided with two banks of teeth 74, diametrically opposite to each other, each occupying one-fourth of the circumference of the mutilated gear, and at the other side the latter is provided with but a single bank of teeth 75, occupying but one-fourth of its circumference. The relative sizes of the mutilated gear 15 and gear 81 are such that each bank of teeth on the former will impart one complete revolution to the latter, and as the bevel-gears 61 are of the same size the longitudinal shaft 60 will make one complete revolution during the time that the mutilated gear 15 does. As said longitudinal shaft during one revolution causes one inward movement of each of the forks 8, two sheaves of grain will be

fed into the trough, and the mutilated gear 15 is so set upon the shaft that just before each sheaf is fed into the trough the mutilated gear will cause the retracting mechanism to draw 5 said trough into position to receive the sheaf, will start the revolution of the knife to cut the band, and will then release the trough, after which one of the smooth faces of the mutilated gear comes opposite the gear, and the 10 trough stands in a distended position for a few moments. If but one side of the machine is to be used and the operator is feeding sheaves of grain upon only one of the tables, the mutilated gear is shifted, so that its single 15 bank of teeth 75 engages the gear, whereby the trough is moved only once during a complete revolution of the shaft 70 and one complete movement of the single fork that is being used, instead of twice, as was necessary 20 when both tables were used, and hence both forks.

36^a is a bar sliding loosely through a hole in the rear cross-beam A and having a slot in its body engaging a vertical pin 104 there- 25 in. The rear end of this bar is pivoted to the crank 103 upon the upper end of the vertical shaft 102, before mentioned, and the outer end of this bar is pivotally connected to a chute 32, which is swung by links 105 below 30 a yoke 106, which may be carried by the thrashing-machine or by a part of the frame-work of this band-cutter and feeder, the chute being vibrated longitudinally by said crank 103, and thereby shaking and spreading the 35 grain as it is delivered from the trough in a manner which will be readily understood. This chute may also be provided with fingers 117, similar to those in the extension O' and for the same purpose.

40 With this construction of parts the operators feed the sheaves onto the hinged tables M, and they are carried by the aprons N onto the tables S, whence they are moved by the forks 8 alternately from one table and the 45 other into the trough O. The revolving knife severs the bands around the sheaves, and the wheat therein is loosened and spread within the trough. The latter is thrown forward at proper moments, and the grain thereby fed 50 into the thrashing-machine over the vibrating chute 32 in a manner which will be well understood, the opening of the wings P permitting the scattering of the grain into said chute. The guides T have feet which stick 55 in the longitudinal slots R in the hinged tables M, and are manually adjustable, whereby the sheaves may be fed at any desired point onto the feed-belts and by them into the trough, and the end piece of the latter is 60 also movable therein, as above described, so that it may be set to the proper position to stand against the lower ends of the sheaves.

What I claim is—

1. In a grain-feeder, the combination, with 65 the stationary table and means for moving a sheaf from the table to the thrasher, of the hinged table having longitudinal slots, an

apron moving transversely upon said hinged table between said slots, and guides having feet frictionally engaging and manually adjustable within said slots at either edge of the apron, substantially as described. 70

2. In a grain-feeder, the combination, with the stationary table, means for moving a sheaf therefrom, a longitudinally-moving trough 75 into which the sheaf is dropped, and a movable end piece therein, of the hinged table having longitudinal slots, an apron moving transversely upon said table, and guides having feet frictionally engaging and manually adjustable within said slots, substantially as described. 80

3. In a band-cutter and feeder, the combination, with the feed-tables and the longitudinally-reciprocating trough between them 85 provided with an end piece having a slot in its rear end, of the revolving band-cutter, substantially as described.

4. In a grain-feeder, the combination, with the feed-tables, of the longitudinally-recipro- 90 cating trough between them having a closed rear end and an extended open front end, wings hinged to the sides of said trough above the extended bottom, and connections be- 95 tween the free ends of said wings and the frame-work of the machine, substantially as described.

5. In a grain-feeder, the combination, with the stationary tables having transverse slots and the forks 8, whose tines extend through 100 said slots and whose bodies are slotted longitudinally, of brackets 3, having pins 63, en- gaging said slotted bodies at the sides of the frame-work, a single bracket 7 below the frame-work having a pin 6, a slotted pitman 105 9, connecting the lower ends of said forks and moving upon said pin in the single bracket, and a crank for imparting motion to the lower end of one of the forks, substantially as and for the purpose set forth. 110

6. In a band-cutter and feeder, the combi- 115 nation, with the trough O, pressed forwardly by a spring and having the block 19, pro- vided with a roller, of a shaft carrying fin- gers alternately engaging and disengaging 120 said roller, a knife-operating shaft 80, con- nected with said finger-shaft, a band-cutting knife driven by said knife-operating shaft, a gear on said shaft, and a rotating mutilated gear engaging said gear, the whole operating substantially as described. 125

7. In a band-cutter and feeder, the combi- 130 nation, with the trough O, having the block 19, provided with rollers 118, and a spring pressing it normally forward, of a rotating shaft having fingers alternately engaging and disengaging the rollers for retracting said trough, a catch for holding the same in re- tracted position, and an adjustable cam on said shaft for tripping said catch, substan- tially as described.

8. In a grain-feeder, the combination, with a vertical rotating cranked shaft, a slotted bar connected to the crank thereof, and a pin

in the frame-work loosely engaging the slot in said bar, of a yoke connected to the frame-work, links depending therefrom, a chute flexibly supported by said links and connected at 5 one end to said bar, feeding-tables, a band-cutter, and a reciprocating trough delivering into said chute, all substantially as described.

In testimony that I claim the foregoing as my own I have hereto affixed my signature in presence of two witnesses.

WILLIAM H. IZARD.
